UNITED STATES PATENT OFFICE.

GEORGE C. HICKS, JR., OF CONNERSVILLE, INDIANA.

PUMP.

1,241,513.

Specification of Letters Patent.

Patented Oct. 2, 1917.

Application filed February 7, 1917. Serial No. 147,051.

To all whom it may concern:

Be it known that I, GEORGE C. HICKS, Jr., a citizen of the United States, residing at Connersville, Fayette county, Indiana, have 5 invented certain new and useful Improvements in Pumps, of which the following is a specification.

This invention, relating to improvements in pumps of the rotary impeller type, will 10 be readily understood from the following description taken in connection with the accompanying drawings in which:—

Figure 1 is a demonstrative diagram:

Fig. 2 a vertical section of a pump exemplifying my invention, the section being in 15 the plane of line *c* of Fig. 3:

Fig. 3 a front elevation of the pump, parts appearing in vertical section in the plane of line *d* of Fig. 2:

20 Fig. 4 a side elevation of the extra elliptical body for controlling the movement of the oscillating abutment; and Fig. 5 a vertical section illustrating a simplified modification of structure.

25 In the drawings, giving consideration for the present entirely to Fig.:.

1, indicates an elliptical disk:

2, a pair of rigidly unified arms having surfaces at right angles to each other and 30 tangential to two points on the periphery of the ellipse:

3, a center on which the pair of arms may oscillate:

4, a circle concentric with the geometrical 35 center of the ellipse and having a radius equal to the distance from that center to the center of oscillation 3 of the arms: and

5, the geometrical center of the ellipse.

If the ellipse be stationary and the pair 40 of arms be carried about the ellipse in the circle 4 and the pair of arms be free to oscillate on the center 3 then the arms will be at all times tangential to two points on the periphery of the ellipse. Conversely, if 45 the center of oscillation 3 be in fixed position and the ellipse be rotated upon its center 5, the two arms will be at all times tangential to two points on the periphery of the ellipse.

50 Proceeding with the drawings:—

6, indicates a pump casing:

7, an inlet thereto for the fluid or liquid to be pumped:

8, the outlet from the casing:

55 9, a shaft mounted for rotation in the

casing and adapted to have power applied to it:

10, an elliptical impeller fast on this shaft:

11, a segmental bore in the casing concentric with the shaft 9 and adapted to be swept by the major extremities of the ellipse, this segmental bore comprehending at least a semi-circle:

12, a port placing the interior of the bore 65 11 in communication with the outlet 8 of the casing:

13, an outwardly opening check-valve closing this port:

14, a shaft mounted in the casing parallel 70 with shaft 9 opposite the segmental bore 11 and sufficiently far from shaft 9 to be freely cleared by the major extremities of the ellipse as the ellipse rotates, this shaft forming a pivot of oscillation for a two-armed 75 oscillating abutment:

15, an abutment mounted for oscillation with shaft 14 as a pivot, this abutment being formed with two rigidly united arms having straight surfaces at right angles to 80 each other and tangential to the periphery of the impeller 10:

16, the extremities of the arms of the abutment, the same being formed on circular arcs struck from the center of shaft 14: 85

17, convex surfaces formed in the casing and adapted to be swept by the extremities of the abutment as the abutment oscillates:

18, the inlet chamber of the casing, formed between the abutment and the casing inlet 90 7: and

19, the casing chamber formed by bore 11 and swept through by the impeller.

The side walls of the casing are in running contact with the sides of the impeller 95 and abutment, as is usual in pumps of the impeller type, and as the impeller rotates it constantly maintains contact with both arms of the abutment, one major extremity of the impeller being always in contact with bore 100 11 and acting to compress the fluid or liquid being dealt with and to bring about its discharge from the casing, check-valve 13 preventing regurgitation, and the extremities of the arms of the abutment maintaining 105 contact with the casing, all in an obvious manner.

The term "contact" has been used above but it is to be understood that it would be highly desirable if there were no such con- 110

tact as would bring about wear due to the rubbing of contacting surfaces. The closeness of fit between the running surfaces is to be as free as is consistent with the nature 5 of the material being pumped, and the lubrication of the rubbing surfaces should be considered. If the pump be used as an oil pump then, of course, the pump will be self-lubricating. And, similarly, but to a lesser 10 degree, if other liquids be dealt with. If the pump is to deal with a fluid, as air, I provide for lubrication of the pump parts by means of water.

Proceeding with the drawings:—

15. 20, indicates a port placing inlet-chamber 18 in communication with impeller-chamber 19 and located above pivot-shaft 14:

21, ports extending through the arms of the abutment at their inner portions where 20 the arms are not engaged by the periphery of the impeller:

22, a chamber disposed between the impeller-chamber and the casing-outlet and lower than port 12:

25. 23, a water-inlet to inlet-chamber 18:

24, a water-outlet from chamber 22: and

25, a line indicating a general level of water in inlet-chamber 18.

Assume the pump to be in motion and 30 handling air. The water in inlet-chamber 18 is subject to the splashing effect of the oscillating abutment. The water lubricates the surfaces 16—17 at the extremities of the abutment, any water leakage past these surfaces going to the impeller-chamber 19, the water at the same time going through openings 21 and serving to lubricate the running surfaces between the impeller and the arms of the abutment, the running of the major 35 extremities of the ellipse against bore 11 being lubricated by the water which leaks down past the extremities of the abutment and by the water which has come down into the impeller-chamber through ports 21.

40. 45. The water passes out with the air through port 12 and becomes trapped in chamber 22 from which it may be withdrawn through water-outlet 24, which should be under valvular control.

50. It is highly desirable that there should be no actual rubbing contact between the periphery of the ellipse and the working faces of the arms of the abutment but that the fitting of these parts to each other should be maintained with satisfactory closeness. In 55 the description thus far given the oscillations of the abutment have been brought about by the action of the impeller upon the arms of the abutment. In order to avoid 60 rubbing contact between these parts, I provide exterior mechanism for oscillating the abutment independent of the impeller.

Proceeding with the drawings:—

65. 26, indicates a housing near the pump-casing:

27, a prolongation of the impeller-shaft, this prolongation being journaled in the housing:

28, a prolongation of shaft 14 forming the pivot-shaft of the abutment, the abutment 70 being fast on its pivot, and the prolongation being journaled in the housing:

29, an oil tank carried by the housing and comprehending the space between the two sidewise separated members of the housing, 75 which housing furnishes two bearings for each of the shafts:

30, an elliptical cam fast on shaft 27 within the oil-tank and corresponding in peripheral contour with the impeller 10: 80

31, a two-armed fork fast upon shaft 28, within the oil-tank, and having two arms with faces at right angles to each other and engaging the periphery of the cam in the same manner that the arms of the abutment 85 engage the periphery of the impeller:

32, adjustable shoes, of any suitable character, forming the functional faces of the arms of fork 31: and

33, oil-inlets to the upper bearings in the 90 housings.

Cam 30 and the arms of the fork have precisely the relationship to each other that the impeller and the arms of the abutment have to each other, but the arms of the fork are in actual rubbing contact with the periphery of the cam. It follows that as the lower shaft is rotated, the abutment is forced to take on its proper oscillations uninfluenced by the impeller and that there is therefore 100 no need of any such rubbing contact between the impeller and the arms of the abutment as would produce disturbing wear. The wear of the arms of the fork and of the periphery of the cam may be compensated 105 for by adjusting the shoes of the fork.

Oil carried in the oil-tank will serve in maintaining a constant satisfactory lubrication of the cam and the arms of the fork. It is preferred that oil be supplied to the 110 upper bearings of the housing through oil inlets 33, the oil serving to lubricate the upper bearings in the housing and flowing thence, through suitable channels, to the lower bearings, and flowing thence into the 115 oil-tank where it is splashed into by the cam.

The modification illustrated in Fig. 5 will be self-explaining, the abutment and the bore in which it oscillates having their arcs or surface so extended that the abutment forms its own axis of oscillation thus avoiding the necessity for the employment of a pivot-shaft for the support of the abutment. 120 125

I claim:—

1. A pump comprising, a casing provided with an inlet and an outlet and with an impeller-chamber having a segmental bore, an impeller-shaft journaled in the casing con- 130

- centric with said bore, an elliptical impeller carried by said shaft and adapted to have its major extremities sweep said bore, a pivot carried by the casing parallel with the 5 impeller-shaft between the impeller and the casing-inlet, an abutment mounted for oscillation on said pivot as an axis and having a pair of arms provided with faces at right angles to each other and tangential to the 10 periphery of the impeller, said oscillating abutment separating the impeller-chamber from the casing-inlet, and means for maintaining the ends of the arms of the abutment in running relationship with the casing 15 as the abutment oscillates, combined substantially as set forth.
2. A pump comprising, a casing provided with an inlet and an outlet and with an impeller-chamber having a segmental bore, an impeller-shaft journaled in the casing concentric with said bore, an elliptical impeller carried by said shaft and adapted to have its major extremities sweep said bore, a pivot carried by the casing parallel with 20 the impeller-shaft between the impeller and the casing-inlet, an abutment mounted for oscillation on said pivot as an axis and having a pair of arms provided with faces at right angles to each other and tangential to the periphery of the impeller, said oscillating abutment separating the impeller-chamber from the casing-inlet and having ports through its arms 25 placing the inlet-chamber and the impeller-chamber in communication with each other, means for maintaining the ends of the arms of the abutment in running relationship with the casing as the abutment oscillates, 30 and means for permitting water supplied to the inlet-chamber to go therefrom past the extremities of the arms of the abutment and to and out of the impeller-chamber combined substantially as set forth. 35
3. A pump comprising, a casing provided with an inlet and inlet-chamber and an outlet and with an impeller-chamber having a segmental bore, an impeller-shaft journaled in the casing concentric with said bore, an elliptical impeller carried by said shaft and 40 adapted to have its major extremities sweep said bore, a pivot carried by the casing parallel with and above the impeller-shaft between the impeller and the casing-inlet, an abutment mounted for oscillation 45 on said pivot as an axis and having a pair of arms provided with faces at right angles to each other and tangential to the periphery of the impeller, said oscillating abutment separating the impeller-chamber from the casing-inlet, means for maintaining the ends of the arms of the abutment in running relationship with the casing as the abutment oscillates, and means for permitting water supplied 50 to the inlet-chamber to go therefrom past the extremities of the arms of the abutment and to and out of the impeller-chamber, said casing being provided with a chamber provided with an outlet and disposed between the impeller-chamber and the casing-outlet and below the latter, combined substantially 55 as set forth.
4. A pump comprising, a casing provided with an inlet and inlet-chamber and an out- 60 let and with an impeller-chamber having a segmental bore, an impeller-shaft journaled in the casing concentric with said bore, an elliptical impeller carried by said shaft and adapted to have its major extremities sweep said bore, a pivot carried by the casing parallel with and above the impeller-shaft between the impeller and the casing-inlet, an abutment mounted for oscillation on said pivot as an axis and having a pair of arms 65 provided with faces at right angles to each other and tangential to the periphery of the impeller, said oscillating abutment separating the impeller-chamber from the casing-inlet and having ports through its arms 70 placing the inlet-chamber and the impeller-chamber in communication with each other, means for maintaining the ends of the arms of the abutment in running relationship with the casing as the abutment oscillates, 75 and means for permitting water supplied to the inlet-chamber to go therefrom past the extremities of the arms of the abutment and to and out of the impeller-chamber combined substantially as set forth. 80
5. A pump comprising, a casing provided with an inlet and inlet-chamber and an outlet and with an impeller-chamber having a segmental bore, an impeller-shaft journaled in the casing concentric with said bore, an elliptical impeller carried by said shaft and adapted to have its major extremities sweep said bore, a pivot carried by the casing parallel with and above the impeller-shaft between the impeller and the casing-inlet, an abutment mounted for oscillation on said pivot as an axis and having a pair of arms 85 provided with faces at right angles to each other and tangential to the periphery of the impeller, said oscillating abutment separating the impeller-chamber from the casing-inlet and having ports through its arms 90 placing the inlet-chamber and the impeller-chamber in communication with each other, means for maintaining the ends of the arms of the abutment in running relationship with the casing as the abutment oscillates, and means for permitting water supplied to the inlet-chamber to go therefrom past the extremities of the arms of the abutment and to and out of the impeller-chamber combined substantially as set forth. 95
6. A pump comprising, a casing provided with an inlet and an outlet and with an impeller-chamber having a segmental bore, an impeller-shaft journaled in the casing concentric with said bore, an elliptical impeller carried by said shaft and adapted to have its major extremities sweep said bore, an abutment-shaft carried by the casing parallel with the impeller-shaft between the impeller 100 and the casing-inlet, an abutment mounted for oscillation on said abutment-shaft as an axis and having a pair of arms provided with faces at right angles to each other and tangential to the periphery of the impeller, said oscillating abutment separating the impeller-chamber from the casing-inlet and having ports through its arms 105 placing the inlet-chamber and the impeller-chamber in communication with each other, means for maintaining the ends of the arms of the abutment in running relationship with the casing as the abutment oscillates, and means for permitting water supplied to the inlet-chamber to go therefrom past the extremities of the arms of the abutment and to and out of the impeller-chamber, said casing being provided with a chamber provided with an outlet and disposed between the impeller-chamber and the casing-outlet and below the latter, combined substantially 110 as set forth. 115
7. A pump comprising, a casing provided with an inlet and an outlet and with an impeller-chamber having a segmental bore, an impeller-shaft journaled in the casing concentric with said bore, an elliptical impeller carried by said shaft and adapted to have its major extremities sweep said bore, an abutment-shaft carried by the casing parallel with the impeller-shaft between the impeller 120 and the casing-inlet, an abutment mounted for oscillation on said abutment-shaft as an axis and having a pair of arms provided with faces at right angles to each other and tangential to the periphery of the impeller, said oscillating abutment separating the impeller-chamber from the casing-inlet and having ports through its arms 125 placing the inlet-chamber and the impeller-chamber in communication with each other, means for maintaining the ends of the arms of the abutment in running relationship with the casing as the abutment oscillates, and means for permitting water supplied to the inlet-chamber to go therefrom past the extremities of the arms of the abutment and to and out of the impeller-chamber, said casing being provided with a chamber provided with an outlet and disposed between the impeller-chamber and the casing-outlet and below the latter, combined substantially 130 as set forth. 135

- and the casing-inlet, an abutment fast on the abutment-shaft and having a pair of arms provided with faces at right angles to each other and tangential to the periphery of the impeller, said oscillating abutment separating the impeller-chamber from the casing-inlet, means for maintaining the ends of the arms of the abutment in running relationship with the casing as the abutment oscillates, prolongations of the abutment-shaft and impeller-shaft, an elliptical cam fast on the prolongation of the impeller-shaft, and a fork fast on the prolongation of the abutment-shaft and having a pair of arms provided with faces at right angles to each other and tangential to the periphery of the cam, combined substantially as set forth.
7. A pump comprising, a casing provided with an inlet and an outlet and with an impeller-chamber having a segmental bore, an impeller-shaft journaled in the casing concentric with said bore, an elliptical impeller carried by said shaft and adapted to have its major extremities sweep said bore, an abutment-shaft carried by the casing parallel with the impeller-shaft between the impeller and the casing-inlet, an abutment fast on the abutment-shaft and having a pair of arms provided with faces at right angles to each other and tangential to the periphery of the impeller, said oscillating abutment separating the impeller-chamber from the casing-inlet, means for maintaining the ends of the arms of the abutment in running relationship with the casing as the abutment oscillates, prolongations of the abutment-shaft and impeller-shaft, an elliptical cam fast on the prolongations of the impeller-shaft, a fork fast on the prolongation of the abutment-shaft and having a pair of arms provided with faces at right angles to each other and tangential to the periphery of the cam, and adjustable shoes on the faces of the arms of the fork, combined substantially as set forth.
8. A pump comprising, a casing provided with an inlet and an outlet and with an impeller-chamber having a segmental bore, an impeller-shaft journaled in the casing concentric with said bore, an elliptical impeller carried by said shaft and adapted to have its major extremities sweep said bore, an abutment-shaft carried by the casing parallel with the impeller-shaft between the impeller and the casing-inlet, an abutment fast on the abutment-shaft and having a pair of arms provided with faces at right angles to each other and tangential to the periphery of the impeller, said oscillating abutment separating the impeller-chamber from the casing-inlet, means for maintaining the ends of the arms of the abutment in running relationship with the casing as the abutment oscillates, prolongations of the abutment-shaft and impeller-shaft, an elliptical cam fast on the prolongations of the impeller-shaft, a fork fast on the prolongation of the abutment-shaft and having a pair of arms pro-

fast on the prolongations of the impeller-shaft, a fork fast on the prolongation of the abutment-shaft and having a pair of arms provided with faces at right angles to each other and tangential to the periphery of the cam, and an oil-tank having a portion disposed below said cam and adapted to contain oil to be splashed into by the cam, combined substantially as set forth.

9. A pump comprising, a casing provided with an inlet and an outlet and with an impeller-chamber having a segmental bore, an impeller-shaft journaled in the casing concentric with said bore, an elliptical impeller carried by said shaft and adapted to have its major extremities sweep said bore, an abutment-shaft carried by the casing parallel with the impeller-shaft between the impeller and the casing-inlet, an abutment fast on the abutment-shaft and having a pair of arms provided with faces at right angles to each other and tangential to the periphery of the impeller, said oscillating abutment separating the impeller-chamber from the casing-inlet, means for maintaining the ends of the arms of the abutment in running relationship with the casing as the abutment oscillates, prolongations of the abutment-shaft and impeller-shaft, an elliptical cam fast on the prolongations of the impeller-shaft, a fork fast on the prolongation of the abutment-shaft and having a pair of arms provided with faces at right angles to each other and tangential to the periphery of the cam, a housing having a pair of side members carrying bearings for the prolongations of the shafts and disposed axially at the sides of the cam and fork, and an oil-tank inclosing the space between the side-members of the housing and inclosing said fork and cam, combined substantially as set forth.

10. A pump comprising, a casing provided with an inlet and an outlet and with an impeller-chamber having a segmental bore, an impeller-shaft journaled in the casing concentric with said bore, an elliptical impeller carried by said shaft and adapted to have its major extremities sweep said bore, an abutment-shaft carried by the casing parallel with the impeller-shaft between the impeller and the casing-inlet, an abutment fast on the abutment-shaft and having a pair of arms provided with faces at right angles to each other and tangential to the periphery of the impeller, said oscillating abutment separating the impeller-chamber from the casing-inlet, means for maintaining the ends of the arms of the abutment in running relationship with the casing as the abutment oscillates, prolongations of the abutment-shaft and impeller-shaft, an elliptical cam fast on the prolongations of the impeller-shaft, a fork fast on the prolongation of the abutment-shaft and having a pair of arms pro-

- vided with faces at right angles to each other and tangential to the periphery of the cam, a housing having a pair of side members carrying bearings for the prolongations of the shafts and disposed axially at the sides of the cam and fork, an oil-tank inclosing the space between the side-members of the housing and inclosing said fork and cam, and oil-passages placing the shaft-bearings 10 in the housing in communication with the oil-tank, combined substantially as set forth.
11. A pump comprising, a casing provided with an inlet and an outlet and with an impeller-chamber having a segmental bore, 15 an impeller-shaft journaled in the casing concentric with said bore, an elliptical im-
- peller carried by said shaft and adapted to have its major extremities sweep said bore, an abutment mounted for oscillation within the casing on an axis parallel with said shaft and provided with radial faces at right angles to each other and tangential to the periphery of the impeller and provided with a concentric peripheral surface, and a concave surface carried by the casing concentric with the axis of the abutment and co-operating with the periphery of the abutment, combined substantially as set forth.
